INSULATED FLOOR STRUCTURE FOR REFRIGERATED SHIPBOARD COMPARTMENTS Hans Heinrich Richard Niemann, Abendrothsweg 33,
Hamburg, Germany

Filed Apr. 3, 1963, Ser. No. 270,468

Claims priority, application Germany Nov. 16, 1955
7 Claims. (Cl. 114—76)

This invention relates to ship construction, and more particularly to an insulated floor structure for refrigerated shipboard compartments, and this application is a continuation-in-part of my co-pending application Serial No. 620,367, filed November 5, 1956, now abandoned.

As is well known, shipboard structures are subject to stresses and strains entirely different from those encountered in structures on land, and furthermore, by the very nature of the shipboard construction, once the structure is completed, access to inner portions thereof is rendered extremely difficult if not impossible, since the interior structures of ships are normally assembled from the bottom thereof upwardly, with the result that succeeding structures cover those situated below, and unless access means is provided in the event it is necessary to have access to inner structures, it is necessary to tear out the succeeding structures, thereby rendering replacement or repair time-consuming and costly.

This situation is particularly troublesome with respect to tanks for water or fuel situated in the bottom of the ship, and covered by compartments, particularly refrigerated compartments in which there is an appreciable difference in temperature between the compartment and the structure located therebelow, and due to the stresses and strains imposed on the structure, it is extremely difficult to provide a moisture-proof floor or bottom for the refrigerated compartment, with the result that leakage of moisture frequently occurs, which moisture collects in the space between the floor of the compartment and the top plates of the tanks situated therebelow, with the result that not only are the tank plates subject to rust and corrosion with subsequent failure thereof, but the insulating material in the floor structure of the refrigerated compartment becomes saturated with moisture, thereby rendering such material substantially useless for insulating purposes.

Furthermore, a portion of the floor structure for the refrigerated compartment is usually of wood construction, and any moisture leakage results in rotting of such wood construction, with the result that periodically a major repair operation is necessary, and with presently utilized construction this operation is time-consuming and costly.

The situation above referred to is further aggravated by the fact that frequently where a refrigerated chamber is installed over fuel oil tanks, it is customary to provide an air space between the floor structure and the top plates of the tanks, and to ventilate such air space by means of a duct leading therefrom to the atmosphere, and while such duct may permit the escape of oil vapor, such duct also permits the entry of moisture to such space, since sea air is usually very humid, and due to the temperature differential between the refrigerated compartment and the space between the floor structure thereof and the tank top plates, condensation occurs which results in moisture from the air collecting in the space, as well as in the insulation, thereby destroying the insulating qualities thereof, and causing rotting of any wood structures present therein, as well as corrosion of the tank top plates.

It is accordingly an object of the invention to provide an insulated floor structure for refrigerated compartments in a ship, which structure may be conveniently prefabricated in relatively small, easily handled units, and there-

2

after installed in the ship to provide a moisture-proof floor structure.

A further object of the invention is to provide an insulated floor structure for refrigerated compartments in a ship, the floor structure being composed of relatively small, conveniently handled, individual units which may be prefabricated and thereafter installed in the ship, such units also being individually removable for replacement or repair, or to provide access to the tank top plate or other structure situated therebelow.

A still further object of the invention is the provision of an insulated floor structure for refrigerated compartments in a ship, in which the insulating material is completely sealed in a moisture-proof container, thereby preventing entry of moisture into the insulation material, to thereby maintain the insulating qualities thereof.

Another object of the invention is the provision of an insulated floor structure for refrigerated compartments in a ship, which floor structure may be conveniently prefabricated in individual units of standard size which may be conveniently installed in the ship, and thereafter individually removed for replacement or repair, and in which means is provided for facilitating the extrusion of a sealing material between the joints of the individual sections after installation thereof in the ship, thereby providing a moisture-proof floor structure.

Further objects and advantages of the invention will be apparent from the following description taken in conjunction with the accompanying drawings, wherein:

30 FIG. 1 is a fragmentary top plan view showing the floor structure of this invention installed in a ship to provide the floor of a refrigerated compartment;

35 FIG. 2, a fragmentary sectional view taken substantially on the line 2—2 of FIG. 1, and showing the relationship of the floor structure of this invention to tanks installed in the bottom of the ship below the floor structure;

40 FIG. 3, a fragmentary sectional view taken substantially on the line 3—3 of FIG. 1, and showing the manner of supporting the floor structure, as well as details of construction thereof, together with the sealing means between each floor structure unit; and,

45 FIG. 4, a fragmentary sectional view taken substantially on line 4—4 of FIG. 1, and showing further details of construction of the floor structure.

With continued reference to the drawings, and particularly FIG. 2, there is shown a portion of a ship having a bottom 10 and a side 11 of conventional construction, and installed in the bottom of the ship are a plurality of tanks 13 for water or fuel, such tanks being separated by partitions 14 and being provided with conventional baffle plates 15 having apertures 16 therein. There is also provided a bilge space 17 having conventional baffle plates 18 therein. Water may collect in the bilge space 17, and may be pumped therefrom at periodic intervals. The tanks 13 are provided with top plates 19, and suitable insulation 20 and 21 may be provided on the side 11 of the ship. The above-described structure represents substantially conventional ship construction, and represents the structure which must receive the insulated floor structure of this invention.

As best shown in FIGS. 1 and 2, the insulated floor structure of this invention comprises a plurality of individual units 22 of generally rectangular configuration, and which may be conveniently prefabricated in a shop on shore to standardized dimensions, and thereafter conveniently installed in the ship. Stanchions for supporting the deck above the compartment having the floor structure of this invention are shown at 23.

With particular reference to FIGS. 2, 3 and 4, each individual floor unit or section 22 comprises a generally rectangular floor plate 24 of any suitable material such as wood, metal or the like, and the floor plate 22 is provided

with an arcuate, outwardly opening groove 25 extending along the side edges 26, and along the end edges 27. As clearly shown in FIGS. 3 and 4, the upper edge 28 of each groove 25 is disposed inwardly of the lower edge for a purpose which will later appear.

A cross member 29 depends from each end of the floor plate 22, and the cross-members 29 may be secured to the floor plate 22 by a bolt 30 extending therethrough, with the head of the bolt disposed in a countersunk recess 31 in the floor plate 22, and with the nut 32 of the bolt 30 disposed in a countersunk recess 33 in the cross member 29. A generally rectangular container 34 of moisture-proof, flexible, yieldable material having side walls 35, end walls 36, and a bottom wall 37 is provided for receiving insulating material 38, and the side walls 35 of the container 34 are provided with outwardly extending flanges 39 on the upper edges thereof. The container 34 depends from the floor plate 24, and as best shown in FIG. 3, the flanges 39 on the side walls 35 of the container 34 are secured to the lower surface of the floor plate 24 by screw-threaded fastening means or the like 40, and as best shown in FIG. 4, the end walls 36 of the container 34 are secured to the outer surface of the cross members 29 by a suitable adhesive or other means, and furthermore, as will be seen from an inspection of FIG. 4, the upper edges 41 of end walls 36 of the container 34 are received in a downwardly opening recess 42 in the end edges of the floor plate 24, and these upper edges 41 of the end walls 36 are secured to a wall of the recess 42 in any suitable manner, as by a suitable adhesive. The upper edges 41 of the end walls 36 of the container 34 which project into the recesses 42 serve to seal the joint 43 between the cross members 29 and the floor plate 24.

Outwardly projecting flexible sealing strips 44 project outwardly from the lower edges of the side walls 35 of the container 34, and the sealing strips 44 may be secured to the bottom wall 37 of the container 34 in any suitable manner, such as by a clamping strip 45 secured to the bottom wall 37. In a similar manner, sealing strips 46 project outwardly from the lower edges of the end walls 36 of the container 34, and the sealing strips 46 may be secured to the bottom wall 37 in any desired manner, such as by clamping strips 47 suitably secured to the bottom wall 37.

In order to support the individual floor sections or units in the ship to provide a floor structure for a refrigerated compartment above the tanks 15, there may be provided spaced, parallel timbers 48, clearly shown in FIGS. 2 and 3, as extending in a fore and aft direction in the ship, and resting on the upper surface of the tank top plates 19. As best shown in FIGS. 2, 3 and 4, the individual floor sections or units 22 are installed in the ship with the containers 34 depending between the timbers 48, and the flanges 39 on the side walls 35 of the containers 34 engage the upper surface of the timbers 48. The floor plates 24 are secured to the timbers 48 by screw-threaded or other suitable fastening means 49 extending downwardly through the floor plates 24, and with the heads of the fastening means 49 received in counter bores 50 in the upper surface of the floor plates 24. The fastening means 49 operates to clamp and compress the flanges 39 between the lower surface of the floor plates 24 and the upper surface of the timbers 48 to provide a moisture-proof seal therebetween. As shown in FIG. 3, the sealing strips 44 on the lower side edges of the containers 34 engage the adjacent side surface of the timbers 48, and in a similar manner, as shown in FIG. 4, the sealing strips 46 on the lower end edges of the containers 34 engage the sealing strips 46 on the adjacent containers. The sealing strip 44 and 46 provide baffles to prevent air circulation upwardly between the containers 34 and between the containers 34 and the timbers 48.

In order to provide a completely moisture-proof structure which will prevent leakage of water downwardly from the compartment through the floor structure to the

space between the tank top plates 19 and the floor structure, it will be seen from an inspection of FIGS. 3 and 4 that the arcuate grooves 25 in the side and end edges of the floor plates 24 provide a space with an opening upwardly through the floor plates provided by the edges 28 set back from the lower edges 26, and the space provided by the arcuate grooves 25 may be conveniently filled by extruding a suitable sealing or calking material 51 into this space. The sealing material 51 does not set hard, but remains in a semi-plastic or yieldable condition to compensate for expansion and contraction of the floor sections, while continuing to provide a moisture-proof seal, and furthermore, such material does not prevent convenient removal of individual floor sections 22 by simply removing the fastening means 49 and lifting the section out in order to permit convenient repair or replacement of the section, or repair of the tank top plates 19 situated therebelow.

As best shown in FIG. 2, a suitable hatch 52 may serve to provide access to the bilge space 17, and if desired, the hatch 52 may be of substantially the same construction as the floor sections 22.

It will be seen that by the above-described invention, there has been provided an insulated floor structure for refrigerated compartments in a ship, which structure may be conveniently and economically prefabricated from readily available materials and in shops on shore, thereby facilitating such fabrication, the sections thereafter which are of standard dimensions being conveniently installed in the ship, it only being necessary to provide the timbers 48 on the tank top plates 19 for supporting the floor sections in place. The structure as above described provides complete moisture protection for the insulation, since such insulation is sealed in a moisture-proof container forming a part of each floor section, and furthermore, complete moisture protection for the space below the floor structure is provided by suitable sealing means installed between the adjacent floor sections during the installation thereof. As the result of the particular structure above described, moisture-proof characteristics and consequently the efficiency of the insulation will be maintained, regardless of stresses and strains resulting from working of the ship in a seaway, and repair or replacement of the floor structure is greatly facilitated by reason of the use of individual sections which may be conveniently removed and replaced, without destroying the entire floor structure.

It will be obvious to those skilled in the art that various changes may be made in the invention without departing from the spirit and scope thereof, and therefore the invention is not limited by that which is shown in the drawings and described in the specification, but only as indicated in the appended claims.

What is claimed is:

1. Insulated floor structure for refrigerated compartments in a ship having a hull, tanks in the bottom of said hull, said tanks having top plates and said compartments being disposed above said tanks, said floor structure comprising a plurality of spaced parallel timbers extending fore and aft in said hull and supported on said top plates, a plurality of substantially identical generally rectangular floor sections disposed between and supported on said timbers, each floor section comprising a generally rectangular floor plate having an arcuate outwardly opening groove extending along the side and end edges and with the upper edge of each groove disposed inwardly of the lower edge, a cross member depending from each end of said floor plate, a generally rectangular container of moisture-proof, flexible, yieldable material having side, end and bottom walls, outwardly extending flanges on the upper edges of said side walls, said container depending from said floor plate and surrounding said cross members with said flanges secured to said floor plate, said floor plate having a downwardly opening recess extending along each end edge, said end walls being secured to the outer

sides of said cross members and to a wall of said recess to seal the joints between said cross members and said floor plate, a mass of insulation in said container and outwardly projecting flexible sealing strips extending along the lower side and end edges of said container, said floor sections being disposed between said timbers with said flanges and a portion of the side edges of each section overlapping said timbers to support said sections thereon with the bottom wall of each section spaced above said top plates, said floor plates being secured to said timbers to compress the material of said flanges and provide a seal, the sealing strips on the sides of said containers engaging the sides of said timbers, the sealing strips on the ends of said containers overlapping and engaging the sealing strips on the ends of the adjacent containers and the opposed grooves in the side and end edges of said floor plates being filled with a plastic caulking compound, whereby a moisture-proof seal is provided between the compartment and the space above said top plates and said floor sections are individually removable for repair or replacement.

2. Insulated floor structure for refrigerated compartments in a ship having a hull, tanks in the bottom of said hull, said tanks having top plates and said compartments being disposed above said tanks, said floor structure comprising a plurality of spaced, parallel timbers extending fore and aft in said hull and supported on said top plates, a plurality of substantially identical generally rectangular floor sections disposed between and supported on said timbers, each floor section comprising a generally rectangular floor plate having an arcuate outwardly opening groove extending along the side and end edges and with the upper edge of each groove disposed inwardly of the lower edge, a cross member depending from each end of said floor plate, a generally rectangular container of moisture-proof, flexible, yieldable material having side, end and bottom walls, outwardly extending flanges on the upper edges of said side walls, said container depending from said floor plate and surrounding said cross members with said flanges secured to said floor plate, said end walls being secured to the outer sides of said cross members and to a wall of said recess to seal the joints between said cross members and said floor plate and a mass of insulation in said container, said floor sections being disposed between said timbers with said flanges and a portion of the side edges of each section overlapping said timbers to support said sections thereon with the bottom wall of each section spaced above said top plates, said floor plates being secured to said timbers to compress the material of said flanges and provide a seal and the opposed grooves in the side and end edges of said floor plates being filled with a plastic caulking compound, whereby a moisture-proof seal is provided between the compartment and the space above said tank plates and said floor sections are individually removable for repair or replacement.

3. Insulated floor structure for refrigerated compartments in a ship having a hull, tanks in the bottom of said hull, said tanks having top plates and said compartments being disposed above said tanks, said floor structure comprising a plurality of spaced parallel timbers extending fore and aft in said hull and supported on said top plates, a plurality of substantially identical generally rectangular floor sections disposed between and supported on said timbers, each floor section comprising a generally rectangular floor plate having an arcuate outwardly opening groove extending along the side and end edges and with the upper edge of each groove disposed inwardly of the lower edge, a cross member depending from each end of said floor plate, a generally rectangular container of moisture-proof, flexible, yieldable material having side, end and bottom walls, outwardly extending flanges on the upper edges of said side walls, said container depending from said floor plate and surrounding said cross members with said flanges secured to said floor plate, said end walls being secured to the outer sides of said cross members and to a wall of said recess to seal the joints between said cross members and said floor plate and a mass of insulation in said container, said floor sections being disposed between said timbers with said flanges and a portion of the side edges of each section overlapping said timbers to support said sections thereon with the bottom wall of each section spaced above said top plates, said floor plates being secured to said timbers to compress the material of said flanges and provide a seal and the opposed grooves in the side and end edges of said floor plates being filled with a plastic caulking compound, whereby a moisture-proof seal is provided between the compartment and the space above said tank plates and said floor sections are individually removable for repair or replacement.

with said flanges secured to said floor plate, said end walls being secured to the outer sides of said cross members and a mass of insulation in said container, said floor sections being disposed between said timbers with said flanges and a portion of the side edges of each section overlapping said timbers to support said sections thereon with the bottom wall of each section spaced above said top plates, said floor plates being secured to said timbers to compress the material of said flanges and provide a seal and the opposed grooves in the side and end edges of said floor plates being filled with a plastic caulking compound, whereby a moisture-proof seal is provided between the compartment and the space above said top plates and said floor sections are individually removable for repair or replacement.

4. Insulated floor structure for refrigerated compartments in a ship having a hull, tanks in the bottom of said hull, said tanks having top plates and said compartments being disposed above said tanks, said floor structure comprising a plurality of spaced parallel timbers extending fore and aft in said hull and supported on said top plates, a plurality of substantially identical generally rectangular floor sections disposed between and supported on said timbers, each floor section comprising a generally rectangular floor plate having an outwardly opening groove extending along the side and end edges, a cross member depending from each end of said floor plate, a generally rectangular container of moisture-proof, flexible, yieldable material having side, end and bottom walls, outwardly extending flanges on the upper edges of said side walls, said container depending from said floor plate and surrounding said cross members with said flanges secured to said floor plate, said end walls being secured to the outer sides of said cross members and a mass of insulation in said container, said floor sections being disposed between said timbers with said flanges and a portion of the side edges of each section overlapping said timbers to support said sections thereon with the bottom wall of each section spaced above said top plates, said floor plates being secured to said timbers to compress the material of said flanges and provide a seal and the opposed grooves in the side and end edges of said floor plates being filled with a plastic caulking compound, whereby a moisture-proof seal is provided between the compartment and the space above said top plates and said floor sections are individually removable for repair or replacement.

5. Insulated floor structure for refrigerated compartments in a ship having a hull, tanks in the bottom of said hull, said tanks having top plates and said compartments being disposed above said tanks, said floor structure comprising a plurality of spaced, parallel timbers extending fore and aft in said hull, a plurality of generally rectangular floor sections disposed between and supported on said timbers, each floor section comprising a generally rectangular floor plate having an outwardly opening groove extending along the side and end edges, a cross member depending from each end of said floor plate, a generally rectangular container of moisture-proof, flexible, yieldable material having side, end and bottom walls, outwardly extending flanges on the upper edges of said side walls, said container depending from said floor plate and surrounding said cross members with said flanges secured to said floor plate, said end walls being secured to the outer sides of said cross members and a mass of insulation in said container, said floor sections being disposed between said timbers with said flanges and a portion of the side edges of each section overlapping said timbers to support said sections thereon with the bottom wall of each section spaced above said top plates, said floor plates being secured to said timbers to compress the material of said flanges and provide a seal and the opposed grooves in the side and end edges of said floor plates being filled with a plastic caulking compound, whereby a moisture-proof seal is provided between the compartment and the space above said top plates and said floor sections are individually removable for repair or replacement.

said top plates and said floor sections are individually removable for repair or replacement.

6. Insulated floor structure for refrigerated compartments in a ship having a hull, tanks in the bottom of said hull, said tanks having top plates and said compartments being disposed above said tanks, said floor structure comprising a plurality of spaced parallel timbers extending fore and aft in said hull, a plurality of generally rectangular floor sections disposed between and supported on said timbers, each floor section comprising a generally rectangular floor plate having an outwardly opening groove extending along the side and end edges, a cross member depending from each end of said floor plate, a generally rectangular container of moisture-proof, flexible, yieldable material having side, end and bottom walls, outwardly extending flanges on the upper edges of said side walls, said container depending from said floor plate and surrounding said cross members with said flanges secured to said floor plate, said end walls being secured to the outer sides of said cross members and a mass of insulation in said container, said floor sections being disposed between said timbers with said flanges and a portion of the side edges of each section overlapping said timbers to support said sections thereon, said floor plates being secured to said timbers to compress the material of said flanges and provide a seal and the opposed grooves in the side and end edges of said floor plates being filled with a plastic caulking compound, whereby a moisture-proof seal is provided and said floor sections are individually removable for repair or replacement.

7. Insulated floor structure for refrigerated compartments in a ship having a hull, tanks in the bottom of said

hull, said tanks having top plates and said compartments being disposed above said tanks, said floor structure comprising a plurality of spaced parallel timbers extending fore and aft in said hull, a plurality of generally rectangular floor sections disposed between and supported on said timbers, each floor section comprising a generally rectangular floor plate having an outwardly opening groove extending along the side and end edges, a cross member depending from each end of said floor plate, a generally rectangular container of moisture-proof material having side, end and bottom walls, outwardly extending flanges on the upper edges of said side walls, said container depending from said floor plate and surrounding said cross members with said flanges secured to said floor plate, said end walls being secured to the outer sides of said cross members and a mass of insulation in said container, said floor sections being disposed between said timbers with said flanges and a portion of the side edges of each section overlapping said timbers to support said sections thereon, said floor plates being secured to said timbers and the opposed grooves in the side and end edges of said floor plates being filled with a plastic caulking compound, whereby a moisture-proof seal is provided and said floor sections are individually removable for repair or replacement.
